U.S. PATENT DOCUMENTS

D396,854 S 8/1998 Tullis
D398,594 S 9/1998 Tullis(57) **CLAIM**The ornamental design for a display screen or portion
thereof with graphical user interface, as shown and
described.**DESCRIPTION**The FIGURE is a front view of a graphical user interface for
a display screen or portion thereof with graphical user
interface showing the claimed design.The outermost dashed broken lines around in the FIGURE
show a display screen or portion thereof and form no part of
the claimed design. The dot-dash broken lines in the FIG-
URE and the areas within the dot-dash broken lines show
portions of the graphical user interface that form no part of
the claimed design. The other dashed broken lines in the
FIGURE show portions of the graphical user interface that
form no part of the claimed design.**1 Claim, 1 Drawing Sheet**# US D795,899 S
